DESIGN FOR A SPOON OR OTHER ARTICLE OF FLATWARE

James Russell Price, Cranston, R. I., assignor to
Gorham Manufacturing Company, Providence,
R. I., a corporation of Rhode Island

Application March 9, 1938, Serial No. 75,686

Term of patent 14 years

To all whom it may concern:

Be it known that I, James Russell Price, a citizen of the United States of America, of 2335 Cranston Street, Cranston, Rhode Island, have invented a new, original, and ornamental Design for a Spoon or Other Article of Flatware, of which the following is a specification, reference being had to the accompanying drawing, forming part thereof.

Fig. 1 is a front elevation of a spoon showing my new design. Fig. 2 is a side elevation of the same. Figs. 3 and 4 are cross sections of the spoon in Fig. 1 on lines 3—3 and 4—4, respectively.

I claim:

The ornamental design for a spoon or other article of flatware, substantially as shown.
JAMES RUSSELL PRICE.
